UNITED STATES PATENT OFFICE.

HERBERT R. KEITHLEY, OF CHICAGO, ILLINOIS.

UNDERFRAME FOR RAILWAY-CARS.

SPECIFICATION forming part of Letters Patent No. 752,231, dated February 16, 1904.

Application filed October 12, 1903. Serial No. 176,654. (No model.)

To all whom it may concern:

Be it known that I, HERBERT R. KEITHLEY, a citizen of the United States, residing at Chicago, in the county of Cook and State of Illinois, have invented new and useful Improvements in Underframes for Railway-Cars, of which the following is a specification.

This invention relates to steel railway-car underframes which are built up of structural shapes and plates, and more particularly to underframes similar to that disclosed in my application for United States Letters Patent filed June 6, 1903, Serial No. 160,385.

The object of the present invention is to provide an underframe of a construction possessing the advantages of the underframe of said application and in which the relative arrangement of the parts is such that the underframe is better adapted for use with wooden-bottom cars, whether of the flat, gondola, or box type.

In the accompanying drawings, consisting of two sheets, Figure 1 is a plan view, partly broken away, of one-half of an underframe embodying the invention. Fig. 2 is a transverse vertical section thereof, on an enlarged scale, in line 2 2, Fig. 1, showing a portion of a wooden floor-frame supported by the underframe. Fig. 3 is a side elevation of one-half of the underframe. Fig. 4 is longitudinal vertical section in line 4 4, Fig. 1. Fig. 5 is a transverse vertical section, on an enlarged scale, in line 5 5, Fig. 1.

Like letters of reference refer to like parts in the several figures.

The underframe is composed of parallel longitudinal side and center sills, each in the form of a built-up plate-girder, end sills, transverse bolsters, which extend from one side sill to the other, and transverse floor-beams, which connect the center and side sills between the bolsters.

Each side sill consists of a vertical web-plate A and upper and lower flanges or chords B and C. The girder side sill is preferably constructed similar to that disclosed in my application for United States Letters Patent filed January 2, 1903, Serial No. 140,003, except that the Z-bar forming the upper chord is arranged, as shown, with its outer flange pro-

jecting downwardly and riveted to the upper portion of the side-sill web-plate, its web extending inwardly from the side-sill web-plate and its inner flange projecting upwardly from the inner edge of its web. The Z-bar is preferably riveted to the inner side of the side web-plate, and its web is reinforced by a horizontal plate b, arranged beneath and riveted to the web of the Z-bar. This plate b preferably terminates at the bolsters. The Z-bar upper chord or flange of the side-sill girder, arranged as above described, gives great lateral stiffness to resist horizontal stresses tending to cause an outward deflection or bulging of the upper portion of the side sill and also lends great vertical stiffness to the side sill. The inwardly-projecting web of the Z-bar affords ample riveting area for connecting the upper portions of the bolsters and floor-beams to the side sill, and at the same time, as will be observed from Fig. 2 of the drawings, the longitudinal wooden side sill of the floor-frame can be supported directly on the web of the Z-bar outside of its upwardly-projecting flange, to which it can be bolted, being thus in an advantageous position for the attachment of the wooden car-floor and siding of the car when the underframe is employed for gondola and box cars. The wooden floor-sill does not extend outwardly beyond the web of the girder side sill, so that vertical stiffeners for the gondola and box car side can be arranged outside of the wooden floor-sill and riveted directly to the web of the girder side sill.

The center sills are arranged in their usual relation, and each sill preferably consists of a vertical web-plate D and upper and lower chords. The lower chord is formed by an angle-bar d, riveted to the lower edge of the web-plate. The upper portions of the webs of the two center sills are connected together, and their upper flanges or chords are formed by a channel-beam E, arranged between the web-plates, with its web horizontal and its flanges depending inside of and riveted to the web-plates of the two center sills. The center sills and side sills are preferably deeper between the bolsters than at their ends. The center sills preferably do not extend to the ends of the under-

- frame, but terminate a short distance beyond the bolster, as shown in Figs. 1 and 4, and separate draft-sills F are employed which extend from the bolsters to the end of the underframe. 5 These draft-sills are preferably formed by channel-beams arranged vertically with their flanges projecting outwardly, their inner ends being located outside of and riveted to the projecting end portions of the center sills. 10 The rivets connecting the channel draft-beams to the center sills pass through the depending flanges of the channel-beam E, connecting the center sills and the vertical flanges of the angles forming the lower chords of the center 15 sills. The attachment is therefore very strong and rigid, while at the same time permitting the removal and replacement of the draft-beams in case of damage to them.
- G represents one of the bolsters, which are 20 arranged in their usual relation and may be of any suitable construction, but are preferably constructed similar to the bolster described in United States Patent No. 725,849, granted to me April 21, 1903. The ends of 25 the bolster extend beneath the inwardly-projecting webs of the Z-bars forming the upper chords of the side sills and are securely attached thereto by rivets or the like.
- H represents transverse floor-beams, which 30 are arranged intermediate of the bolsters and extend from the center sills to the side sills, being securely attached to both the center and side sills in any approved manner. In the 35 construction shown two of the floor-beams H, which are arranged in line on opposite sides of the center-sill structure, are connected by a horizontal plate, which extends transversely over the center-sill structure and is riveted to the upper flanges of the floor-beams and web 40 of the channel-beam E connecting the center sills. These same floor-beams are shown as connected to the side sills by gusset-plates J, arranged between and riveted to the upper flanges of the floor-beams and the webs of the 45 Z-bars and horizontal plates forming the upper chords of the sills.

I claim as my invention—

1. In an underframe, a plate-girder side sill, comprising a web-plate, and a Z-bar arranged with its web horizontal and projecting laterally inward from the web-plate of said side sill, one flange depending and riveted to said web-plate of the side sill, and the other flange projecting upwardly, substantially as set forth. 50

2. In an underframe, a plate-girder side sill comprising a vertical web-plate, a Z-bar arranged with its web horizontal and projecting laterally inward from the web-plate of said side sill, one flange depending and riveted to the inner side of said vertical web-plate, and the other flange projecting upwardly, and a horizontal plate arranged beneath and riveted to the web of said Z-bar, substantially as set forth. 60

3. In an underframe, the combination of side sills, each comprising a vertical web-plate, and a Z-bar arranged with its web horizontal and projecting laterally inward from said vertical web-plate, one flange depending and riveted to said vertical web-plate, and the other flange projecting upwardly, and bolsters connecting said side sills, the ends of said bolsters extending beneath and being secured to the webs of said Z-bars of the side sills, substantially as 70 set forth. 75

4. The combination of center sills having vertical web-plates, a channel-beam arranged between said center sills with its web horizontal and its flanges depending and riveted to said center-sill web-plates, draft-beams arranged beside the ends of said center sills, and rivets or the like connecting said draft-sills to said center-sill web-plates and said channel-beam flanges, substantially as set forth. 80 85

Witness my hand this 9th day of October, 1903.

HERBERT R. KEITHLEY.
